UNITED STATES PATENT OFFICE.

GEORGE HEINEMAN, OF PHILADELPHIA, PENNSYLVANIA.

SHELL-HOLDER FOR ELECTRIC CUT-OUTS.

1,274,543.

Specification of Letters Patent.

Patented Aug. 6, 1918.

Application filed June 22, 1917. Serial No. 176,292.

To all whom it may concern:

Be it known that I, GEORGE HEINEMAN, a citizen of the United States, residing in the city and county of Philadelphia, State of Pennsylvania, have invented a new and useful Shell-Holder for Electric Cut-Outs, of which the following is a specification.

My invention consists of a holder for the shell of an electric cut out, the same being 10 of novel, simple, and inexpensive construction as will be hereinafter set forth.

It consists also of a novel holder of the character stated, the same comprising an open frame, a neck, and an eye formed from 15 a plate of suitable material in which said eye and neck are punched out of the portion of said plate of which said open frame is constructed, thus effecting a vast saving of material and consequent expense.

20 The invention is satisfactorily illustrated in the accompanying drawing, but the important instrumentalities thereof may be varied, and so it is to be understood that the invention is not limited to the specific 25 details shown and described, as long as they are within the spirit or scope of the claims.

Figure 1 represents a perspective view of a shell holder for an electric cut out embodying my invention.

30 Fig. 2 represents a longitudinal section thereof on line 2—2, Fig. 1.

Fig. 3 represents a top or plan view of the holder and shell.

Fig. 4 represents a central section of the 35 device and its connections on an enlarged scale.

Fig. 5 represents a perspective view of the shell.

Fig. 6 represents a central section thereof.

40 Fig. 7 represents a plan view showing the method of producing the holders.

Similar numerals of reference indicate corresponding parts in the drawings.

Referring to the drawings:—

45 1 designates the porcelain base of an electric cut-out, and 2 designates a shell which occupies the tubular portion thereof, and is adapted to receive a fuse-plug usual in such cases.

50 3 designates the holder for said shell, the same consisting of the open frame 4, the neck 5 extending from a side thereof, and a head with an opening therein forming the eye 6, said head being on the outer 55 terminal of said neck.

On the periphery of said eye are the

turned-up lips 7 which are spaced apart and designed as guards to receive between them an electric wire or conductor and prevent shifting of the same from said eye, the opening in the latter being adapted to receive the screw 8, which by means of the washer 9 serves to connect said wire or conductor with said eye.

In the side of the shell 2 is the throat 10 which forms a passage for the insertion of the frame 4 of the holder 3 into said shell, said frame when so inserted being adapted to rest on the bottom flange 11 of said shell. A screw 12 is passed through the washer 13 70 which rests on the top of the frame 4 of the holder 3, and also through said frame, and the bottom wall of the base 1, its threaded end engaging the threaded sleeve or nut 14 in said base whereby said frame may be connected with said bottom wall of the base 1, and the shell 2 retained firmly within the tubular portion of said base. This is assisted by the action of the screw 8 in its engagement with the adjacent portion of the 75 base 1, as shown at the left side of Fig. 4.

In the manufacture of the holder 3, I take a plate of suitable metal and punch out of the same the contour of the eye 6, the lips 7 and the neck 5, and I cut the plate across 80 from the inner terminal of said neck right and left on the lines 15 to the side edges of the plate thus producing the contour of the open frame 4, it being noticed that said neck, eye and lips are removed from the adjacent 85 portion of the plate that comprises said open frame, thus effecting a vast saving of material and consequent reduction of expense in the manufacture of the holder, it being noticed that the opening in said frame admits the securing screw 12 passing through the same into the base, while also reducing the weight of the frame portion of the holder and admitting of sufficient surface of the latter to be supported flat on the flange 11 of 90 the shell.

The lips as punched out as in Fig. 7 are subsequently turned up at an angle to the periphery of the eye as shown in Fig. 1, and the other figures.

105 It will be seen that a portion of a side of the frame punched or cut out forms the opening 16 in said side and the material removed therefrom comprises the neck of the adjacent holder, and so there is a utilization 110 of a portion of the material of which said open frame is formed to produce said neck

and eye of an adjacent holder which is a vast saving of material in the manufacture of the holders in that the neck and eye of one holder are made within the confines of the 5 open frame of the adjacent holder.

The plate of the eye 6 is coincident in size with the opening in the frame 4, and the lips 7 of the head are coincident in size with the recesses 17 in the wall of said opening. The 10 neck 5 is coincident in size with the opening 16. Consequently, in cutting or punching out the eye-head, the lips 7 are formed therewith.

Having thus described my invention what 15 I claim as new and desire to secure by Letters Patent, is:—

1. The combination of a shell having a bottom flange and a throat in its side, with an open frame having a neck, said frame and 20 neck resting upon said flange with an eye extended through said throat and having bendable flanges, fastening means passing

through said eye, securing means passed through said bottom of the shell, and means beneath the bottom of the shell for retaining 25 said securing means.

2. The combination of a shell having a bottom flange and a throat in its side, with an open frame having a neck, said frame and neck resting upon said flange with an eye 30 extended through said throat and having bendable flanges, fastening means passing through said eye, a washer resting upon the open frame, securing means passed through the bottom of the shell, and means below the 35 bottom of the latter for retaining said securing means, said shell having in its side a throat forming a passage for the insertion of said open frame.

GEORGE HEINEMAN.
